UNITED STATES PATENT OFFICE.

KENNETH J. UNWIN, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

GUARD FOR WEFT DETECTORS IN LOOM TRANSFERRERS.

Application filed December 27, 1926. Serial No. 157,078.

This invention relates to improvements in weft detectors of the type mounted on regularly moving transerrer arms and it is the principal object of the invention to provide means for holding the detector out of contact with the supply of weft until exhaustion approaches.

In weft detectors of the type set forth in patent to Ryon No. 1,872,316 the transerrer arm is moved toward the surface to be detected on each detecting beat of the loom and the weft detector is moved downwardly through the top of the shuttle to have engagement with the weft. As heretofore made the transerrer arm and detector have had a detecting movement every alternating beat of the loom, but where rayon is used it is found that the same supply of weft is active for such a length of time that the repeated contacts with the detector results in fraying or abrasion of the yarn. It is an important object of my present invention to provide means for holding the detector out of contact with a full supply of weft and to release the same so that it may have engagement with the weft only as exhaustion approaches.

It is a more particular object of my invention to provide a guard which will engage but not injure the weft and be movable when an abundance of weft is present into holding engagement with respect to the detector, the guard acting when the diameter of the weft is reduced to permit the detector to have a weft engaging movement.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown,

Fig. 1 is a central vertical section through that portion of a transerrer arm which lies over the surface to be detected when the lay is on the magazine side of the loom and holding the detector away from the weft with the guard in contact with a full supply of filling.

Fig. 2 is a view similar to a portion of Fig. 1 but with the guard in such position as to release the detector with the latter in con-

tact with a reduced supply of weft sufficient for several picks,

Fig. 3 is a view similar to Fig. 1 but with the detector released and in engagement with the bare bobbin and moving to indicating position, and

Fig. 4 is a vertical section on line 4—4 of Fig. 1 showing the guard.

Referring to the drawings, transerrer arm 10 is provided with a pair of spaced walls 11 between which extend a yarn engaging tip 12 and a bobbin butt engaging heel 13. An indicating plunger 14 is disposed for horizontal sliding movement in a portion of the transerrer arm and is normally constrained to move from the position shown in Fig. 1 to that shown in Fig. 3 by a compression spring 15. Said plunger is provided with a notch 16 and may have a pin 17 to engage a web 18 for limiting outward movement of the plunger.

The plunger is retained in non-indicating position by means of a latch 19 having a hook 20 to enter the notch 16 and having also a depending tail 21. A torsion spring 22 surrounds a pin 23 on which the latch is pivoted and has one end thereof in engagement with the transerrer arm as at 24 and the other end in engagement with the latch as at 25. The effect of the spring is to hold the latch yieldingly in the position shown in Fig. 1.

The detector carrier comprises a lever 26 pivoted to the transerrer arm as at 27 and having a hook 28 which receives one end of a tension spring 29. The other end of said spring is anchored to the transerrer arm as at 30 so that said spring tends normally to hold the lever 26 in raised position as shown in Fig. 1, said lever being positioned by having finger 31 thereof in engagement with web 18.

It is to be understood that on each detecting beat the transerrer arm is given a downward movement and as the same reaches the bottom of its stroke the lever 26, having practically all its weight on one side of the pin 27, will tend to move downwardly due to the inertia thereof. The matter thus far described is of common construction and forms no part of my present invention.

In carrying my improvements into effect I provide a detector 40 pivoted to the lever

as at 41 and having a positioning finger 42 which engages a portion of the lever and holds the weft engaging teeth 44 to one side of the stud 41. The detector member 40 is provided with a lug 45 having a holding face which is inclined upwardly and toward the stud 41 to define with the member 40 a pocket or notch 46.

A guard 47 is pivoted as at 48 to the trans-
ferrer arm and is normally held in the position shown in Fig. 3 by a small tension spring 49 interposed between a portion of the guard and a fixed part of the transferrer. Said guard has a substantially horizontal arm 50 having on the lower end thereof a pad 51, which, if desired, may be of relatively soft material, such as felt or leather. The lower face of this pad may be convex with respect to the surface of the bobbin B so as to slide over the convolutions of weft without producing fraying or abrasion. The upper portion of the arm 50 is provided with a tooth 52 which enters the notch 46.

Under normal conditions when the trans-
ferrer arm is raised the lever 26 will be held upwardly by the spring 29 and the detector 40 will be held in the position shown in Fig. 1 with respect to the transferrer. The guard will be in the position indicated in dotted lines in Fig. 1 so that the tooth 52 is below and to one side of the notch 46. As the transferrer arm descends toward a full supply of weft the pad 51 will engage the bobbin and be moved upwardly relatively to the transferrer arm and cause tooth 52 to enter notch 46. As the transferrer arm comes to rest at the bottom of its stroke the inertia of the lever 26 will tend to keep the same moving downwardly but the lug 45 overhanging the tooth 52 will prevent such downward movement due to the fact that the pad is held by yarn on the bobbin. Under these conditions the parts will be in the position shown in Fig. 1.

As weaving continues a time will come when that portion of the bobbin immediately under the pad 51 will be uncovered so that as the transferrer arm moves downwardly the guard will not be given an upward movement around its center 48. As the transferrer arm reaches the bottom of its movement under these conditions the lug 45 will be out of contact with the tooth 52 and the detector will be free to move downwardly and into engagement with the weft as the inertia of lever 26 moves the same downwardly. If sufficient weft is still on the bobbin for the weaving of several picks the detector will be restrained against sliding movement toward the tail 21 and the plunger 14 will remain locked even though the detector is unlocked.

At a subsequent time the amount of weft remaining on the bobbin will be insufficient for continued weaving at which time the

detector 40, still being unlocked because of the lowered position of the guard 47, will move along the denuded bobbin and into contact with the tail 21 of the latch to move the latter to the position shown in Fig. 3, thus releasing plunger 14 to permit spring 15 to move the same to the indicating position shown in said Fig. 3. Upon the upward movement of the transferrer arm an indicating lever, not shown herein but set forth in the aforesaid patent to Ryon, will be engaged by the plunger to initiate replenishment.

As soon as a full bobbin has been transferred into the shuttle the guard 47 will again be moved upwardly relatively to the transferrer arm into detector restraining or locking position to hold the teeth of said detector away from the weft, and this relation will continue until the new bobbin assumes a condition similar to that indicated in Fig. 2.

From the foregoing it will be seen that I have provided a weft detecting mechanism for a regularly moving transferrer wherein the teeth of the detector are held away from the weft until the latter has been depleted sufficiently to render detection on each detecting beat of the loom desirable. It will further be seen that the pad 51, although in contact with the bobbin on all detecting beats of the loom, is formed with a smooth lower surface such as will not abrade the weft. Although I have shown this pad as leather or fibre yet I do not wish to be limited to these materials as any substance presenting a smooth or soft surface to the weft will suffice. It will further be seen that the guard is located in such a position that the detector will be released in time to permit the same to have engagement with the weft during the latter part of the time that the bobbin is active and when the remaining amount of yarn is such that a new surface is exposed each successive detecting beat of the loom.

Having thus described my invention it will be apparent that changes and modifications may be made therein by those skilled in the art without departing from the spirit and scope of the invention and I do not wish to be limited to the details herein disclosed, but what I claim is:

1. In weft detecting mechanism for a loom having a transferrer arm receiving a movement toward the surface to be detected each detecting beat of the loom, a weft detector, a carrier therefor movably mounted on the transferrer arm, and a guard pivoted to the transferrer arm and movable by an abundant supply of weft into holding engagement with respect to the detector to hold the latter out of contact with the weft.

2. In weft detecting mechanism for a loom having a transferrer arm receiving regular

movements at periodic intervals toward the supply of weft to be detected, a weft detector mounted on the transerrer arm and movable with respect thereto toward the surface to be detected in a fixed path, a guard mounted on the transerrer arm and normally positioned to be engaged by the surface to be detected and being movable under influence of the surface being detected, in a fixed path which intersects the path of the detector, said guard being moved by an abundant supply of weft so that the same intersects the path of the detector to hold the latter out of engaging position with the surface to be detected and said guard being moved by a depleted supply of weft a distance insufficient to intersect the path of movement of the detector, whereby the latter may have detecting engagement with the surface to be detected.

3. In weft detecting mechanism for a loom having a transerrer arm receiving regular

movements at periodic intervals toward the supply of weft to be detected, a weft detector mounted on and movable with respect to the transerrer arm and moving in a fixed arc toward the surface to be detected, a guard pivoted to the detector and normally positioned for engagement with the surface to be detected and movable under influence of the surface in an arc of the path which intersects the path of movement of the detector, said guard being moved by a sufficient supply of weft to intersect the path of the detector to prevent engagement of the latter with the surface to be detected and said guard when engaged by an insufficient supply of weft failing to intersect the path of the detector, whereby the latter may have engagement with the surface to be detected.

In testimony whereof I have hereunto affixed my signature.

KENNETH J. UNWIN.
